UNITED STATES PATENT OFFICE.

HENRY COWARD WORTH EMERY AND EDMUND CHRISTIAN, OF LONDON,
ENGLAND.

TOBACCO-PIPE.

SPECIFICATION forming part of Letters Patent No. 408,341, dated August 6, 1889.

Application filed November 6, 1888. Serial No. 290,156. (No model.) Patented in England September 6, 1888, No. 12,883.

To all whom it may concern:

Be it known that we, HENRY COWARD WORTH EMERY, of Lausanne Road, London, and EDMUND CHRISTIAN, of St. John Street, 5 London, subjects of the Queen of Great Britain, have invented certain new and useful Improvements in Tobacco-Pipes, (for which we have obtained British Patent No. 12,883, September 6, 1888;) and we do hereby declare the following to be a full, clear, and exact description of the invention, reference being had to the accompanying drawings, which form part of this specification.

Our invention relates to pipes ordinarily 15 used for smoking tobacco, and it is applicable to such pipes, whether they are made of wood, clay, meerschaum, or other material.

In the accompanying drawings, Figure 1 shows a pipe made according to our invention. Fig. 2 is a longitudinal section through the same; and Fig. 3 is a view from above with the mouth-piece removed. Fig. 4 represents a modification in side elevation.

The object of our improvement is to prevent or reduce the waste of tobacco caused 25 in ordinary pipes by the accumulation of moisture and nicotine, to protect the ignited tobacco from rain and wind, to enable the pipe to be replenished with tobacco without 30 relighting, and to prevent the entry into the tube and mouth-piece of the pipe of nicotine or other injurious moisture.

In the drawings, *a* is the bowl of the pipe, provided with a tube *b*, and mouth-piece 35 of any of the ordinary well-known kinds. The passage through the tube *b* does not pass into the bowl *a* directly, but communicates with the lower end of a channel or passage *c* in the side of the bowl, the upper end 40 of which passage communicates with the upper end of the bowl through the lateral opening *c'*. The ends of the vertical passage *c* are closed. A plug or cover *d* is fitted into the upper end of the bowl *a*, into which it 45 may be screwed or otherwise fixed, so as to make, preferably, as air-tight a joint as possible, and the lower end of the bowl is open, but is preferably provided with a movable perforated cover *e*.

50 In order to use the improved pipe, the plug or cover *d* is removed and the bowl *a* is filled

with tobacco and the plug *d* is replaced. A light is then applied to the lower open end of the bowl and the smoke is drawn by the smoker through the tobacco and through the 55 opening *c'* into the passage *c*, and thence to the mouth-piece. When the tobacco is exhausted, or nearly so, the plug *d* is again removed and a fresh supply of tobacco introduced at the top and pressed down, the 60 ashes being discharged at the bottom and the fresh tobacco being ignited by that remaining in the bowl, if any.

ff represent bars or pins fixed across the bowl *a* near the bottom, to support the tobacco when the latter is pressed into the bowl and prevent it from interfering with the discharge of the ashes or the cleaning of the pipe, as it would if allowed to be pressed quite down to the lower movable cover *e*. 70

The lower movable cover *e* may be of perforated metal or other material, and it may be screwed in or arranged to turn upon a pivot, as shown, or it may be made to slide transversely. It may be made with grooves 75 or openings for the admission of air upon its edges, (as illustrated in Fig. 4,) so as to prevent the falling of sparks or ashes.

The arrangement and relative proportions of the several parts may be varied more or 80 less, according to the character and material of the pipe to which our invention is to be applied.

We claim—

1. A pipe-bowl open at top and bottom 85 and provided with pins extending across it near the latter, in combination with the tube *b*, leading to the mouth-piece, a movable top cover, and a movable perforated bottom cover, for the purpose set forth. 90

2. A pipe having a bowl provided with a movable perforated bottom, and pins extending across said bowl a little above the same, substantially as set forth.

In testimony that we claim the foregoing we 95 have hereunto set our hands, this 13th day of October, 1888.

HENRY COWARD WORTH EMERY.
EDMUND CHRISTIAN.
